SOUND TRANSLATING DEVICE

Herbert R. Warnke, Camden, N. J., assignor to
Radio Corporation of America, New York, N. Y.,
a corporation of Delaware

Application October 29, 1932, Serial No. 640,171

10 Claims. (Cl. 179—115.5)

My invention relates to sound translating devices and, more particularly, to loudspeakers of the movable coil or dynamic type having a permanent magnet field and a large direct-acting 5 conical diaphragm.

In the construction of dynamic loudspeakers having a permanent magnet field, with which I have been familiar, large unwieldy field yokes, usually comprising a multiplicity of bars, have 10 been employed and the construction has been lacking in the simplicity, compactness, and ruggedness characteristic of certain makes of dynamic speakers of the electromagnetic type.

In these permanent magnet field dynamic 15 speakers, it has been the practice heretofore to secure the parts together by means of bolts, clamps, or the like. In such structures, the field magnet has usually been of extremely hard chrome-steel and it has been necessary to soften 20 the metal by special heat treatment prior to forming a large hole in the field yoke for the purpose of securing the center pole piece thereto. It has been found, however, that this operation weakens the material appreciably and, upon subsequent 25 hardening of the metal, considerable trouble has been experienced because of a tendency of the yoke to crack and deform from its previous shape.

In other respects, prior constructions of the 30 above character lacked certain desirable features, particularly in regard to cost of manufacture and magnetic efficiency considered from the standpoint of magnetomotive force in relation to weight and bulk of material used in the field structure.

It is, accordingly, an object of my invention to provide a dynamic speaker of the type having a permanent magnet field and a diaphragm of the direct acting type having appreciable active area 40 and depth, that shall be compact in form and particularly adapted for use in automobile installations where space is quite limited.

A further object of my invention is to provide a permanent magnet field structure for a 45 dynamic loudspeaker, having considerably increased magnetic efficiency, with a minimum of weight and bulk of magnetic material used.

A still further object of my invention is to provide a permanent magnet field structure for a 50 loudspeaker of the dynamic type, whereby the manufacture and assembly thereof may be facilitated and the operation and adjustments incident thereto requiring great skill, may be simplified, 55 thereby resulting in a device that may be manu-

factured in quantities with a high degree of uniformity and low cost.

The invention will, however, be better understood when taken in connection with the accompanying drawing, and its scope will be pointed out in the appended claims.

Referring to the drawing, Fig. 1 is a rear view in perspective and on a reduced scale, of a dynamic loudspeaker embodying my invention;

Fig. 2 is a side view in section, slightly enlarged 10 of the device shown in Fig. 1, and including in addition, a housing structure; and

Fig. 3 is a side view of a modification of the field yoke structure of the device shown in Figs. 1 and 2 and embodying my invention. 15

According to one phase of my invention, a permanent magnet field structure for a cone type dynamic speaker is constructed, preferably of a single yoke bar, to produce a magnetic field of great strength by means of a field yoke structure 20 so formed and arranged with respect to the back of the cone diaphragm that a permanent magnet yoke of relatively great length is possible without any substantial waste of available space from front to back of the speaker, thereby producing a 25 compact, simple, and highly efficient structure. I am aware of the fact that compact dynamic cone speaker constructions have been made in the past, e. g. by placing the dynamic field structure entirely or partially within the concave side 30 of the cone diaphragm, e. g. in the manner disclosed in application of A. Ringel, Serial No. 515,190, filed February 12, 1931, and assigned to RCA Victor Company, Inc., Camden, New Jersey.

Referring to Figs. 1 and 2, the sound translating device shown is a dynamic loudspeaker of the permanent magnet field type, representing a preferred embodiment of my invention, and includes a permanent magnet in the form of a wide U-shaped yoke member 1 of chrome-steel in conjunction with a relatively short inner pole piece 3 of ferro-magnetic material, e. g. cold rolled steel, secured at its lower end to the yoke, preferably by electric arc fillet welding. The lower end of the pole piece 3 is preferably enlarged or flanged to form a flux plate 4 which provides a better support and gives a larger volume of material as well as a greater area of magnetic contact to thereby reduce the reluctance. One of a pair of diametrically opposite fillet welds is 50 shown at 11 along a lower edge of the flange or the flux plate 4. The upper end of the center pole piece 3 terminates at a point appreciably below the level of the ends of the U yoke member 1. 45

An inwardly bent yoke plate 5, which bridges 55

the yoke magnet 1, is made of ferro-magnetic material, e. g. soft iron of high permeability, and serves as a pole piece for the permanent magnet field yoke 1. The yoke plate 5 is provided 5 with a central opening 7 in the inwardly directed portion for cooperating with the center pole piece 3, and is secured at its ends, preferably on opposite sides thereof, to the outer ends of the U-shaped yoke, preferably by electric arc 10 fillet welding, as shown at 9 in Fig. 1. During welding, the parts are held in such manner that the circular opening is in concentric relation with the pole piece, thereby forming an annular air gap. The abutting faces of the yoke plate 5 15 and the ends of the U, as well as the bottom face of the flange 4 on the inner pole piece and the face of the yoke in contact therewith, are all surface-ground prior to assembly and welding. The parts are assembled by means of a special 20 form that is adapted to hold the parts in assembled and spaced relation during the welding process, the novel structure being particularly adapted for assembly by the foregoing operations. A voice coil and form 13 attached to the small end 25 of a frusto conical diaphragm 15 is supported for vibration in the air gap, a resilient spider 16 being secured to the cone and attached to the magnetic structure, preferably to the free end of the inner pole piece for centering the coil in said 30 gap.

For the purpose of supporting the base of the diaphragm, a bracket structure is provided therefor by securing, as by welding in similar manner, an annular metallic ring 17 preferably to the 35 outer ends of the yoke plate 5. A treated fabric structure 19, for flexibly supporting the base of the cone, and attached thereto, is firmly clamped between this ring 17 and an adjacent metallic ring 21 adapted to be held together, as by 40 rivets 23.

The ends of the permanent magnet field yoke 1 are preferably joined to the ends of the yoke plate 5 adjacent to or substantially in the same plane with the base of the cone. The yoke plate 45 5, which constitutes part of the cone supporting bracket structure, is inwardly bent substantially in conformity with the contour of the conical diaphragm and into operative association with the shortened inner pole piece. While I have 50 shown, as my preferred embodiment, a bracket structure formed by securing the ring 17 directly to the ends of the yoke plate 5, for supporting the cone, it should be obvious that a separate bracket structure not associated with the ends of 55 the yoke plate could be provided for the diaphragm. If desired, the ring 17 and yoke plate 5 could be integrally formed out of a single plate.

The foregoing field structure is especially 60 adapted to be magnetized after the assembly has been completed. It is particularly necessary to magnetize after assembly because of the fact that, if the field yoke is magnetized beforehand, as has been previously, of necessity, done in many cases, by reason of the construction, the 65 strong magnetic field tends to attract stray particles of iron to the air gap, and it has been found quite difficult and impractical to free the gap of such particles after they are once there.

While the yoke bar 1 appears to be one magnet, and is so structurally, magnetically it is two magnets in parallel, each being constituted by the portion from the middle of the bar at the inner pole piece to an outer end of the U. The ends of 70 the U are of one and the same polarity, while 75

the middle portion is of the opposite polarity. This arrangement has resulted in a highly efficient structure, giving a strong intense magnetic field, and it has been particularly well adapted to available materials. It has been found, for 5 example, practicable to harden magnet chrome-steel bars of a thickness of only about $\frac{3}{8}$ inch, the thickness of the yoke bar used in speakers built in accordance with my invention. In order to obtain the necessary flux at the air gap for 10 proper operation, it has been found necessary, when using magnetic material of the above nature, to employ a plurality of bars physically, as well as magnetically, in parallel. In one construction with which I am familiar, a pair of 15 bent magnet bars were used in parallel in a superposed co-extensive relation, with their opposite ends attached to the two pole pieces respectively. The resulting structure was quite 20 unsymmetrical and proved difficult to manufacture.

As shown in Fig. 2, the speaker assembly is mounted in a sheet metal housing 27, preferably of non-magnetic material, such as aluminum, by means of bolts 29 that pass through the annular 25 rings 17 and 21 on the assembly and an inwardly turned flange 31 on the housing. The rear end of the metal housing is open except for a covering of fabric 33 in order to prevent the entrance of foreign particles into the assembly while not 30 interfering with the free passage of sound waves. The front of the housing is likewise covered with a protecting layer of fabric 34. The housing is supported at its rear by means of a bracket 35 adapted to be attached in automobiles to a surface of substantial area, as to the dashboard 37, and is preferably spaced therefrom, as shown, for desired acoustic effects.

Referring to Fig. 3, I have shown a modified structure that makes possible a still more efficient arrangement wherein the permanent magnet field yoke is lengthened by bowing outwardly the sides 2 of the U, thereby giving a higher magnetomotive force. The ends of the U extend inwardly into engagement with the yoke plate 5 at points spaced a short distance from the ends of said plate. This arrangement permits a shortening of the magnetic path through the iron yoke plate in the manner shown, which is 45 desirable. The yoke plate 5, preferably drop-forged, is preferably provided with offset portions 43 having parallel ground faces for contacting with the angularly faced ends of the field yoke at 41. The angular face formed on the ends of the inwardly bent U at 41 results in a greater 50 area of contact between the ground surfaces, and thereby appreciably lowers the magnetomotive force loss at the juncture between the pole portions.

Several features of my above construction 55 have been shown and/or described, but not claimed, in the application of Creager et al, Serial No. 589,824, filed January 30, 1932, assigned to the same assignee, and now U. S. Patent No. 2,027,473.

By means of my above described novel arrangements, the efficiency of the field structure of the permanent magnet dynamic device has been greatly increased over prior constructions by reason of the construction that permits the employment of a yoke of relatively great length 60 and cross-section. At the same time, a compact arrangement, particularly in the direction from front to back, has been effected by reason 65 of the fact of the novel combination or associa- 70 75

tion of the magnetic field and conical diaphragm structure. Furthermore, my novel structure has made possible the production of a relatively inexpensive construction that is particularly adapted to large quantity production with a high degree of uniformity in the output.

I claim as my invention:

1. In a permanent magnet field system for a sound translating device of the dynamic type, a U-shape bar of extremely hard ferro magnetic material, the sides of said U being inwardly bent, an inner pole piece attached at one end to the back of said U-shape yoke, and an inwardly directed yoke plate adapted to form a magnetic circuit and an air gap between the ends of the said U and the other end of said inner pole piece, said yoke plate having offset portions adjacent its ends for attachment to the ends of said U-shape yoke.
2. In a permanent magnet loud speaker of the electrodynamic type, the combination of a wide permanent magnet of rectangular cross section, a cylindrical pole piece secured to one side of and extending at a right angle to the intermediate portion of said magnet, and a flux plate disposed between said pole piece and the magnet, said flux plate extending at both sides of the pole piece to the edges of said magnet to provide a low reluctance magnetic flux path between the magnet and said pole piece.
3. In a permanent magnet loud speaker of the electrodynamic type, the combination of a wide permanent magnet of rectangular cross section having its ends of the same polarity and its intermediate area of another polarity, a round pole piece secured to said magnet at its intermediate area and projecting outwardly therefrom, and a flux plate disposed between said pole piece and said magnet, said flux plate extending from the pole piece to the edges of the magnet whereby substantially all of the magnetic flux at the intermediate area of the magnet will be directed into the pole piece.
4. In an electrodynamic loud speaker, the combination of a U-shaped permanent magnet of rectangular cross section having ends of the same polarity and an intermediate area of another polarity, a round pole piece of magnetic material secured upon said U-shaped magnet at its intermediate area and projecting between and parallel with its ends, a bridging member of soft iron welded to the ends of said U-shaped member having an aperture into which the end of said round pole piece projects to form an annular air gap of magnetic flux, and means between said round pole piece and the intermediate area of the magnet for directing the magnetic flux at the intermediate area of the magnet into said pole piece.
5. A permanent magnet field structure for an electrodynamic loud speaker, comprising a permanent bar magnet of rectangular cross section having ends of the same polarity disposed in spaced parallel relation and its middle portion of another polarity, an iron pole piece secured across the ends of said bar magnet and having its middle portion disposed inwardly between the ends of the magnet in spaced parallel relation with the middle portion of the magnet, a cylindrical iron pole piece mounted upon and projecting from the middle portion of the magnet for completing a magnetic circuit between the first pole piece and the middle portion of the magnet, and means engaging

the full width of said bar magnet at its middle portion for directing the magnetic flux of the magnet into said cylindrical pole piece.

6. A permanent magnet field structure for an electrodynamic loud speaker, comprising a permanent magnet of rectangular cross section having its ends of the same polarity and its intermediate portion of another polarity, the ends of said permanent magnet being disposed at a right angle to the intermediate portion of the magnet, a short pole piece of round cross section secured between the ends of said permanent magnet and projecting in the same direction as said ends, said short pole piece having a length less than that of the ends of the permanent magnet, a magnetic flux conducting member secured across the ends of said permanent magnet having its middle portion perforated and disposed inwardly about the end of said pole piece to thereby shorten the magnetic flux path between the ends of said permanent magnet and its intermediate polarized portion, and a high permeability flux directing member disposed between said short pole piece and the intermediate portion of said permanent magnet.

7. In an electrodynamic loud speaker, the combination of a U-shaped member of magnetized steel having ends of the same polarity, a pole piece of magnetic material secured upon said U-shaped member intermediate and parallel with the ends thereof, a bridging member of soft iron secured across the ends of said U-shaped member having an aperture into which the end of said pole piece projects to form an annular air gap, and a flux directing member of magnetic material intrposed between said pole piece and the intermediate portion of said U-shaped member.

8. In an electrodynamic sound reproducing device of the character employing a permanent magnet for maintaining a magnetic flux in its air gap, the combination of a U-shaped member of rectangular cross section formed of magnetized steel, an outer pole piece member having an aperture therein secured upon said U-shaped member at a point of one polarity, an inner pole piece member of round cross section having one end disposed within the aperture of said outer pole piece member to form an air gap and the other end adjacent a point of another polarity on said U-shaped member, and means at the latter end of said inner pole piece engaging the full width of said U-shaped member for providing a magnetic path of low reluctance between said inner pole piece and said U-shaped member.

9. The invention set forth in claim 2 characterized in that said cylindrical pole-piece and said flux plate are constituted by an integral structure and characterized further in that said flux plate is welded to said magnet.

10. The invention set forth in claim 6 characterized by the addition of a substantially conical diaphragm provided with a voice coil, said voice coil being disposed in said aperture and about the adjacent end of said short pole-piece, and characterized further in that said magnetic flux conducting member is disposed inwardly substantially in conformity with the contour of said diaphragm into cooperative association with said short pole-piece.

HERBERT R. WARNE.
